(No Model.)

S. DARLING.
SCREW THREAD GAGE.

No. 552,238.

Patented Dec. 31, 1895.

UNITED STATES PATENT OFFICE.

SAMUEL DARLING, OF PROVIDENCE, RHODE ISLAND.

SCREW-THREAD GAGE.

SPECIFICATION forming part of Letters Patent No. 552,238, dated December 31, 1895.

Application filed September 5, 1895. Serial No. 561,477. (No model.)

To all whom it may concern:

Be it known that I, SAMUEL DARLING, a citizen of the United States, residing at Providence, in the State of Rhode Island, have invented a new and useful Improvement in Screw-Thread Gages, of which the following is a specification.

My invention consists in providing an intermediate stop for oppositely-arranged series 10 of gage-plates, which are held upon a single pivot, in improved means for conveniently opening the said plates from the handle, and in improved means for determining the variety of gages in the handle and the exact location 15 of the gage-plate in the series when the said gage-plates are closed into the handle, with the indicating-figures upon the gage-plates concealed from view.

In the accompanying drawings, Figure 1 20 represents a side view of a screw-thread gage embodying my invention, showing a number of the gage-plates opened from the handle. Fig. 2 represents an edge view of the same. Fig. 3 represents a side view with a single 25 gage-plate opened from the handle for use. Fig. 4 represents a side view of a single gage-plate removed from the handle. Figs. 5 and 6 are side views showing a modification and an improved system of numbering.

30 In the drawings, A represents the handle, composed of two flat metallic strips a a, held at a suitable distance apart by means of the connecting-studs b b', riveted over the outer side of the strips composing the handle. The 35 screw-thread gages d d' are cut at the opposite ends of the gage-plates C C, the gages d being cut in a longitudinal direction upon the edge of the gage-plate and adapted for use as a gage for internal screw-threads, while a

40 gages d', which are made with a pitch corresponding to the pitch of the thread-gage at the opposite end, are cut transversely of the gage-plate at the opposite end and adapted for use as a gage for external screw-threads, the said 45 gage-plates being arranged in opposite series upon a single pivot-stud b, so as to fold into the handle upon opposite sides of the stop-stud b', the gage-plates of one series being arranged alternately with the gage-plates of the 50 opposite series, whereby a space c will be left between the narrow portions of the gage-plates, which greatly facilitates the selection

of the different gage-plates for use. When one of the gage-plates is turned at a right angle with the handle, as shown in Fig. 3, one 55 projecting end of the said gage-plate is adapted to be used as a handle when gaging a screw-thread with the opposite end of the gage-plate.

The ends of the gage-plates are provided 60 with the projections h, which extend beyond the end of the handle A to furnish a ready means for opening the same from the handle.

Each of the gage-plates is marked in the usual manner with the pitch or number of 65 threads to an inch in the gage, and these numbers are repeated upon the handle in the same order in which the gage-plates of the series are arranged upon the pivot. The user can determine at a glance by the order of the numbers upon the handle the definite location in 70 the series of the gage-plates required.

A modification is shown in Figs. 5 and 6, in which the gages are cut obliquely at one end only of the gage-plates and arranged in opposite series upon a single pivot-stud b, so as to fold into the handle upon opposite sides of the stop-stud b', and upon the handle at either side of the central row of figures, which serve to indicate the relative position in the series 80 of the gage required, are placed smaller figures indicating other pitches of screw-threads, for the measurement of which the thread-gage indicated by the larger stamped numbers are applicable. Thus referring to Fig. 5, the gage 85 marked 10 may also be used for gaging screw-threads of five and of twenty pitch. Therefore with this system of numbering a smaller number of gages may be employed in the handle to gage threads of the various pitches required.

I claim as my invention—

1. The combination of the handle provided with the stop for the inner edges of the gage plates, with the screw thread gage plates arranged upon opposite sides of the stop, and connected to the handle by means of a single pivot, substantially as described.

2. The combination of the handle provided with the stop for the inner edges of the gage plates, with the screw thread gage-plates arranged upon opposite sides of the stop, and connected to the handle by means of a single pivot, the said gage-plates being provided at

their ends with a projection, whereby the gage-plates may be readily opened from their closed position in the handle, substantially as described.

5 3. The combination of the handle, with the screw-thread gage-plates held upon a single pivot, the said gage-plates being provided at one end with a thread gage extending longitudinally of the plate, and at the opposite end 10 with a corresponding thread gage extending transversely of the plate, the said gage plates when in use extending from the opposite sides of the handle substantially as described.

4. In a screw-thread gage, a series of gage-
15 plates arranged upon a pivot, and provided at one of their sides with numbers which indicate the number of teeth to the inch in the gages cut on the plates, in combination with

the same numbers, arranged on a single plate, in the same order that the correspondingly 20 numbered gage-plates are arranged on the pivot.

5. In a screw-thread gage, a series of gage-plates arranged upon a pivot, and provided at one of their sides with numbers which indicate the number of teeth to the inch in the gages cut on the plates, in combination with 25 the same numbers arranged on a single plate, and having in connection therewith certain numbers which serve to indicate other pitches 30 of screw threads to which each specific gage-plate is applicable.

SAML. DARLING.
